BAG

Ludwig S. Schlessinger, New York, N. Y.

Application January 10, 1950, Serial No. 7,141

Term of patent 7 years

(Cl. D87—3)

To all whom it may concern:

Be it known that I, Ludwig S. Schlessinger, a citizen of the United States of America, residing in the city of New York, county of New York, State of New York, have invented a new, original, and ornamental Design for a Bag, of which the following is a specification, reference being had to the accompanying drawings, forming a part thereof, wherein:

Fig. 1 is a perspective view of one side of a bag, showing my new design; and

Fig. 2 is an elevational view of the opposite side of the bag.

The essential features of my design reside in the portion shown in full lines, the design being characterized by the strap closed side pocket on one side associated with the handle ending at said side pocket in combination with the ring attached handle on the otherwise plain opposite side.

I claim:

The ornamental design for a bag, substantially as shown and described.

LUDWIG S. SCHLESSINGER.
